UNITED STATES PATENT OFFICE

HARRY J. GINSBERG, OF CHICAGO, ILLINOIS, ASSIGNOR TO H. T. WINDSOR, OF
BATAVIA, ILLINOIS

SIGN HOLDER

Application filed June 12, 1928, Serial No. 284,752.

The present invention relates to improvements in sign holders and has reference more particularly to a holder for placards or routing cards for use upon railroad cars and tank cars, as well as other places having similar uses.

A further and important object is to provide a sign holder that embodies certain improvements over the sign holder disclosed in my co-pending application, bearing Serial 270,771, filed April 17, 1928, now Patent No. 1,705,564, granted Mar. 19, 1929.

One of the important objects of the present invention is to provide a sign holder having a base constructed in such a manner as to provide a means for receiving and supporting the rod on which is pivotally mounted the sign clamping frame.

Still a further object is to provide a sign holder of the above mentioned character which is simple in construction, inexpensive, strong and durable, and further well adapted to the purpose for which it is designed.

Other objects of the invention will become apparent as the description of the invention proceeds and when taken in connection with the accompanying drawings.

In the accompanying drawings, forming a part of this application and in which like numerals designate like parts throughout the several views:

Figure 1 is a perspective view of the sign holder embodying my invention.

Figure 2 is an enlarged sectional view, taken approximately upon the line 2—2 of Figure 1.

Figure 3 is a detail bottom plan of one end portion of the base showing the eye portion that is formed for receiving either end of the frame supporting rod.

Figure 4 is a sectional view, taken approximately on the line 4—4 of Figure 5, looking downwardly.

Figure 5 is an enlarged elevational view of the upper portion of the base for more clearly showing the finger gripping portion of the inverted U-shaped frame.

Figure 6 is a fragmentary elevational view of the lower right hand corner of the sign holder, and

Figure 7 is an enlarged sectional view, taken approximately on the line 7—7 of Figure 6, looking in the direction of the arrows.

In the drawings, wherein for the purpose of illustration is shown the preferred embodiment of my invention, the numeral 1 designates a substantially rectangular shaped base that is formed preferably from a piece of sheet metal, the same being formed with suitable openings 2, to accommodate appropriate fastening means whereby the base may be secured in a rigid manner on a support provided therefor.

One side edge of the base is formed with the forwardly projecting flange 3, that provides a stop for limiting the sliding movement of the placard or sign in one direction on the base. The base 1 is furthermore formed with an elongated horizontally disposed slot 4, in the upper intermediate portion thereof and the purpose of this slot will be hereinafter more fully described.

The flange 3 terminates at its lower edge in spaced relation with respect to the lower edge of the base 1 and the base is formed with the upwardly extending slits stamped inwardly of the side edges thereof whereby to provide corner tongues 6 and each of these tongues is bent back upon itself or rolled to form a horizontally disposed alined eye or loop 7. Each of these eye portions is slit as at 8, adjacent the outer end thereof whereby to provide a bendable locking strip 9, the purpose of which will be presently described.

A horizontally disposed rod 10 extends across the front face of the lower edge portion of the base 1 and the ends of this rod are disposed within the respective eyes or loops 7, the strips 9 being bent inwardly, in the manner as shown in Figure 7, to prevent displacement of the rod from the eyes, it being understood, of course, that the ends of the rods extend inwardly of the inner edge of the respective locking strips as suggested by the dotted lines in Figure 6.

The invention further comprehends the provision of the substantially inverted U-shaped clamping frame designated generally by the numerals 11, the same being formed from a single strand of spring wire. The

arms 12 of this inverted U-shaped clamping frame have their lower free ends bent to form eyes 13, through which the rod 10 extends, thereby providing a pivotal connection for the clamping frame or bail.

The bight portion 14 of the U-shaped clamping frame or bail has its intermediate portion so bent as to form rearwardly extending loops 15, and a forwardly intermediate disposed loop 16. The rearwardly disposed loop 15 projects through the slot 4, while the forwardly projecting loop 16 extends a considerable distance from the front side of the base, whereby a finger may be inserted between the looped portion 16 and the base, to permit the clamping frame to be readily and easily engaged to swing the same forwardly whenever it is necessary to insert or remove a placard from the sign holder. In Figures 4 and 5, there is shown the specific construction of the intermediate portion of the crown portion of the inverted U-shaped clamping frame or bail.

A pair of axial coil springs 17 encircle the rod 10 adjacent the respective eye portions 13 and each axial coil spring is constructed so as to provide a relatively short arm 18, and a relatively long arm 19 at its ends.

The shorter arm of each axial coil spring extends downwardly and has its free end bent to form a hook 20 that engages with a notch 21 formed in the lower edge of the base 1.

The longer arm 19 of each axial coil spring unit extends upwardly along the adjacent side of the inverted U-shaped clamping frame or bail, the extremities of these arms being bent to form laterally extending hooks 22 that engage over and around the intermediate portions of the respective arms of the inverted U-shaped frame. As the purpose of these coil springs has been fully explained in my co-pending application referred to above, a further description of the function of the springs is believed unnecessary.

It will thus be seen that I have provided an improved sign holder that can be manufactured at a very low cost and the clamping frame will positively support or secure a placard or sign against the front side of the base 1. Furthermore, the sign or placard can be readily and easily removed by swinging the clamping frame forwardly on the rod 10.

While I have shown the preferred embodiment of my invention, it is to be understood that various changes in the size, shape and arrangement of parts may be resorted to, without departing from the spirit of the invention or the scope of the appended claims.

Having thus described my invention, what I claim as new is:

1. In a sign holder, a base constructed from

a single blank of sheet metal having its lower corner portions slotted vertically to establish lower corner supporting lugs, said lugs being bent forwardly then downwardly and rearwardly to establish rod supporting sockets, the lower rearwardly extending portions aforesaid being slotted to establish relatively narrow edge tines, a horizontal rod extending between and supported by the sockets aforesaid, said tines having their rear ends bent upwardly to lock the end portions of the rod in place, a U-shaped clamping member having its lower ends journaled on said horizontal rod adjacent to said corner supports, and suitable spring means tending to swing said clamping member upwardly and into contact with the base member, substantially as described.

2. In a sign holder, the combination with a suitable base member, of a U-shaped clamping member having its lower ends pivotally mounted with respect to the lower corners of said base member, there being a horizontal slotted opening in the base member in alignment with the upper portion of the U-shaped clamping member, and the upper portion of the U-shaped clamping member being bent rearwardly and then forwardly and then rearwardly and again forwardly to establish a V-shaped finger piece lying in a horizontal plane when the clamping member is in clamping position, and extending partially into the horizontal slotted opening of the base member aforesaid, when the clamping member is in clamping engagement with the base member, substantially as described.

In testimony whereof I affix my signature.

HARRY J. GINSBERG.
